UNITED STATES PATENT OFFICE.

ANDREW WINDEN, OF MADELIA, MINNESOTA.

TRANSMISSION APPARATUS.

1,009,204.

Specification of Letters Patent. Patented Nov. 21, 1911.

Application filed May 23, 1911. Serial No. 628,023.

To all whom it may concern:

Be it known that I, ANDREW WINDEN, a citizen of the United States, residing at Madelia, in the county of Watonwan and State of Minnesota, have invented a new and useful Transmission Apparatus, of which the following is a specification.

This invention relates to apparatus for transmitting power and more particularly to mechanism of this character adapted to be actuated by the drive wheels of a motor vehicle whereby a vehicle of such type may be employed as a means for driving machinery of different kinds.

One of the objects of the invention is to provide apparatus of this character which is simple in construction and on which the drive wheels of the motor vehicle can be readily placed, means being provided for holding the drive shaft of the mechanism against rotation while the vehicle is being brought into position thereon.

A further object is to provide means whereby the mechanism can be quickly adjusted to different sized drive wheels.

With the foregoing and other objects in view which will appear as the description proceeds, the invention resides in the combination and arrangement of parts and in the details of construction hereinafter described and claimed it being understood that changes in the precise embodiment of the invention herein disclosed can be made within the scope of what is claimed without departing from the spirit of the invention.

In the accompanying drawings the preferred form of the invention has been shown.

In said drawings:—Figure 1 is a side elevation of the apparatus, a portion of the motor vehicle being shown in position thereabove, the lock being removed. Fig. 2 is a plan view of the parts shown in Fig. 1, the drive wheels of the motor vehicle being shown in dotted lines. Fig. 3 is an enlarged vertical transverse section through a portion of the apparatus. Fig. 4 is an elevation of the locking wheel. Fig. 5 is a detail view of one of the bearing blocks mounted for sliding movement. Fig. 6 is a detail view of the locking mechanism and showing the shaft released.

Referring to the figures by characters of reference 1 designates side sills which, if desired, can be mounted upon end supports 2, these supports being connected by cross

strips 3 preferably inclined as shown and which serve to hold the sills in fixed relation to each other.

Bearing blocks 4 are secured upon the sills 1 adjacent one end and a shaft 5 is journaled therein and carries rolls 6. Bearing blocks 7 straddle the upper edges of the sills and are adapted to slide thereon, each of these blocks being provided at its sides with longitudinal flanges 8 projecting under guide rails 9 secured to the side faces of the sills, the bearing blocks projecting between the sills and the rails. Each bearing block has a cap 10 fastened thereon and a shaft 11 is journaled upon the blocks and is parallel with shaft 5, this shaft 11 carrying spools 12. A disk 13 is secured to and rotates with shaft 11 and has a series of openings 14 extending transversely therethrough, certain of these openings being designed to receive locking pins 15 which are slidably mounted between one of the bearing blocks 7 and its cap 10. These pins are connected to a head 16 and a spring 17 serves to draw the head 16 toward the bearing block so as to normally project the pins 15 against the disk 13. A shifting lever 18 is pivotally mounted on the head 16 and a spring 19 is connected to the lever and to the head 16 and serves, when said head is drawn away from the adjacent bearing, to automatically shift the lever 18 about its pivot so as to hold the head 16 and the pins 15 against movement toward the disk 13. This arrangement of parts has been clearly indicated in Fig. 6.

A lever 20 is fulcrumed upon one of the connecting strips 3 and links 21 extend from the lever to the shaft 11, these links being loosely connected to the shaft. Any suitable means, such as a toothed segment 22 and a pawl 23 may be provided for the purpose of locking the lever in any position to which it may be adjusted.

In using the apparatus herein described, lever 18 is swung so as to place its spring 19 under stress and spring 17 promptly draws the head 16 toward the adjacent sill 1 so as to force the pins 15 against disk 13. By then rotating this disk certain of the apertures therein will be brought into register with the pins and the pins will therefore move into the apertures and thus lock the shaft 11 against rotation. The motor vehicle to be used for actuating the mechanism is then backed onto the structure and with its rear or propelling wheels in engage-

ment with the spools 12 and, as these spools are locked against rotation, it will be apparent that the wheels can be caused to move readily onto the spools and over them and finally into contact with the rolls 6, these rolls and the spools thus coöperating to hold the propelling wheels of the vehicle in position upon the apparatus. These propelling wheels have been indicated at A in Figs. 1 and 2. It will be apparent of course that the shaft 11 can be shifted toward or away from the shaft 5 so as to fit the apparatus to wheels of different diameters. After the wheels have been placed in position on the apparatus, the head 16 is drawn away from the sill 1 and lever 18 promptly swings about its pivot so as to lock the head against return movement. Pins 15 are thus withdrawn from engagement with disk 13 and shaft 11 is free to revolve when the motor on the vehicle is started and power transmitted therefrom to the wheels A. A pulley 24 or the like may be secured to the shaft 11 and motion may be transmitted therefrom, as through a belt 25, to any suitable mechanism to be actuated.

When it is desired to remove the vehicle from the apparatus, it is merely necessary to first lock the shaft 11 against rotation, after which, by rotating the wheels A, they can be caused to move off of the spools 12 and onto the ground.

What is claimed is:—

1. Apparatus for transmitting power, including a supporting structure, shafts journaled thereon, revoluble wheel engaging and supporting devices upon the shafts, means for shifting one of said shafts toward or away from the other shaft, means for locking said shafts against shifting movement, and means for locking one of the wheel engaging devices against rotation.

2. Apparatus for transmitting power, including a supporting structure, parallel shafts journaled thereon, revoluble wheel supporting and engaging devices upon the shafts, means for shifting one of the shafts toward or away from the other shaft, means for holding said shaft against shifting movement, and means for locking said shiftable shaft against rotation.

3. Apparatus for transmitting power, including a supporting structure, parallel shafts journaled thereon, slidable bearing boxes for one of the shafts, means for shifting said shaft to vary the distance between the two shafts, means for locking the shaft in any position to which it may be moved,

and revoluble wheel engaging and supporting devices upon the shafts.

4. Apparatus for transmitting power, including a supporting structure, shafts mounted for rotation thereon, revoluble wheel engaging and supporting devices upon the shafts, a disk revoluble with one of said devices, spring controlled locking fingers normally engaging the disk to hold the said device against rotation, and means for locking the fingers out of engagement with the disk.

5. Apparatus for transmitting power, including connected side sills, bearing boxes straddling and slidably mounted on the sills, guide rails secured to the sills and extending across the boxes, means on said boxes and engaging the rails for holding said boxes against removal from the sills, a shaft journaled upon said bearing boxes, another shaft journaled upon the sills, means for shifting the movable boxes to vary the distance between the shafts, revoluble wheel supporting and engaging devices carried by the shafts, and means for locking one of the shafts against rotation.

6. Apparatus for transmitting power including a supporting structure, parallel shafts journaled thereon, slidable bearing boxes for one of the shafts, means for shifting said boxes to vary the distance between the two shafts, means for locking the said shiftable shaft in any position to which it may be moved, and revoluble wheel engaging devices upon the shafts coöperating to support a wheel with its axis in a plane extending vertically between the axes of said devices.

7. Apparatus for transmitting power, including a supporting structure, parallel shafts journaled thereon, means for shifting one of said shafts to vary the distance between the two shafts, means for locking the said shaft in any position to which it may be moved, means for locking said shaft against rotation, and revoluble wheel engaging devices upon the shafts and coöperating to support a wheel of a motor vehicle with its axis in a vertical plane extending between the axes of the said devices.

In testimony that I claim the foregoing as my own, I have hereto affixed my signature in the presence of two witnesses.

ANDREW WINDEN.
